UNITED STATES PATENT OFFICE.

JOHN W. McLAUGHLIN, OF FAIRMONT, WEST VIRGINIA, AND GEORGE H. GELL, OF SOUTH CLINCHFIELD, VIRGINIA, ASSIGNEES TO CLINCHFIELD CARBON COAL CORPORATION, OF BRISTOL, VIRGINIA, A CORPORATION OF VIRGINIA.

FURNACE RETORT.

Application filed June 20, 1921. Serial No. 478,673.

To all whom it may concern:

Be it known that we, JOHN W. McLAUGHLIN, a citizen of the United States, and a resident of Fairmont, county of Marion, and State of West Virginia, and GEORGE H. GELL, a subject of the King of Great Britain (who has declared his intention of becoming a citizen of the United States of America), and a resident of South Clinchfield, in the county of Russell and State of Virginia, have jointly invented new and useful Improvements in Furnace Retorts, of which the following is a specification.

The invention relates to a furnace-retort wherein coal or analogous material is partially carbonized or subjected to a partial distillation and the present invention is particularly concerned with a furnace-retort wherein the retort has a shell which is revolvably mounted and which is provided with means in the form of a bar or rod, as a railroad rail, to aid in effecting the agitation of the material within the retort and to break up masses of the material within the retort as the shell rotates.

The railroad rail or bar is also relied upon to prevent the depositing of substantial incrustations on the interior of the retort or to effect a removal of incrustations should such become deposited upon the interior of the retort shell. According to the preferred embodiment of the invention the retort shell has hollow trunnions at each end thereof and the hollow trunnion at the discharge end has a freely movable chain to assist in the clearing of the material, to wit, the partially carbonized coal residue, as the latter passes from the interior of the shell on the outward path through the trunnion.

In the Smith Patent No. 1,224,424, dated May 1, 1917, there is described a process and apparatus for treating coal and according to the invention of said patent there is employed a retort wherein coal is agitated or mixed during a heating operation and in which the amount of heat applied to the coal during the period of application is less than the amount required for ultimate destructive distillation; also in the Smith Patent No. 1,276,429, dated Aug. 20, 1918, there is shown and described a retort which is provided with mixing and conveying means for agitating and mixing the ma-

terial while it is being subjected to a partial distillation.

The present invention relates to a retort which is designed to effect a preliminary or partial distillation of the coal while mixing or agitating the coal, and it is useful in performing the inventions of either of the 60 patents above recited.

As showing a specific embodiment of the present invention, reference is made to the accompanying drawings forming a part of this specification, in which drawings;

Figure 1 is a vertical, longitudinal view, partly in section, showing the masonry structure of the furnace of the furnace-retort with the shell of the retort of the furnace-retort rotatably mounted in reference 70 to the masonry structure;

Figure 2 is a vertical, sectional view taken on the plane indicated by line 2—2 of Figure 1 looking in the direction of the arrows;

Figure 3 is a plan view of the structure 75 shown in Figure 1; and

Figure 4 is a vertical, partial end view looking towards the discharge end of the furnace-retort and in this end view there is shown a part of the offtake pipe by means 80 of which vapors and gases can pass from the interior of the retort to any suitable gas cleaning and scrubbing apparatus.

Referring now to the drawings in detail the masonry of the furnace-retort is designated by 1 and is constructed so as to provide suitable heat interchanging means as 2, whereby the air for supporting combustion is suitably preheated by the heat which it receives from the outgoing products of combustion leaving the combustion chamber or combustion space 3 of the furnace of the furnace-retort. The details whereby this heat interchange is accomplished is known to engineers skilled in this 95 class of work and further description thereof is not necessary at this time, it being sufficient to say that the preheated air may enter as at 4 to support this combustion of the gas which is delivered from the piping as 100 at 5.

The retort of the furnace-retort comprises a revolvable shell 6, which includes a longitudinally extending tubular body member 7 with flanges 8, at each end thereof. To the 105 flanges 8 of this tubular body member there

is secured at each end a head as head 9 or 10. Each head has a hollow trunnion as 11 or 12. For each trunnion there is also a bearing member, as bearing member 13, for trunnion 11 and bearing member 14 for trunnion 12. The head 9, with trunnion 11, is at the charging end of the retort shell and there is provided suitable means as 15, whereby the coal or analogous material is fed into the interior of the retort shell through trunnion 11. The feeding means is constructed so that the intake through trunnion 11 is practically gas or air tight whereby gases and vapors are prevented from passing outwardly through this trunnion. As a part in this construction a gas tight joint is provided at 16 between the end of the rotatable trunnion 11, and a relatively fixed member of the feeding-in mechanism 15. Means as 17 with clutch as at 18, is provided for effecting the rotation when desired of the retort shell as a whole, and it will be herewith remarked that the retort shell is continuously rotated when the retort is functioning. The trunnion 11 is frequently referred to as the trunnion at the feed or intake end of the retort. The hollow trunnion 12 at the other end is referred to as the trunnion at the discharge end of the retort and the outermost end of trunnion 12 enters a hollow stationary member 19, constituting a part of the discharge mechanism 20, whereby the partially distilled coal residues can be passed from the retort to the places desired. The construction of the discharge mechanism is such that the residues from the retort can be passed to the places desired without permitting the escape of gases or vapors from the interior of the retort through the discharge mechanism or without permitting the entrance of air into the retort.

The retort, or in other words, casing member 19 thereof, is provided with suitable gas offtake means as piping 21, whereby the gas and vapors evolved during partial carbonization or distillation process can pass from the retort for the desired disposition as to the gas cleaning and scrubbing apparatus and to the holder.

An air or gas tight joint is provided as at 22 between the hollow trunnion 12 on the one hand and the stationary casing 19 on the other. The trunnions at each end of the body member of the retort shell are centrally located, or in other words, the common axis of the two trunnions constitute the axis about which the body member of the retort shell rotates. Within the retort shell or body member thereof there is located a longitudinally extending bar or rod, preferably in the form of a railroad rail, and this bar or rail constitutes a member which effects or assists in effecting the agitating of the material while the retort

shell is being rotated. It also serves to crush any masses tending to form within the retort shell thus keeping the charge within the retort shell in such condition that heat can permeate all portions thereof, and thus permitting to be realized a uniform and progressive heating of the charge within the retort.

The bar or rail 23 also serves to prevent the formation of any incrustations on the interior of the retort shell or at least serve to effect a removal of incrustations which may become deposited upon the interior of the retort shell, should there be such. The bar or rail is freely movable, in other words, it is free to rise and fall as the retort shell is rotating, this automatically accomplishes the ends desired. The specific form of the bar, to wit, in the form of a railroad rail, which has a head, web and bottom flanges is particularly useful in that the flange portions serve not only to crush but to actually cut by the falling of the rail. A rail therefore has the cutting effect similar to that of a dull chisel, or a series of chisels, and because of this characteristic, is particularly advantageous at this place.

A chain, as 24, is located within and practically extends through the hollow trunnion 12 at the discharge end of the retort. This chain is secured at one end as 25, merely to retain the chain in place but otherwise the chain is free to move within the hollow trunnion 12. The chain may therefore be properly described as a freely movable chain and it functions to assist in the clearing of the material as it passes from the interior of the retort through the trunnion on its way to the discharge mechanism.

The residue delivered from the retort is relatively small, the larger particles being about the size of a pea.

The shell of the retort may be of any suitable material which will withstand the work that it must perform and which will also permit the transfer of heat from its exterior through the walls thereof to the material being treated therein. The material preferably employed for this purpose is steel, semisteel or cast iron.

It will be manifest that the invention may be realized in many ways and may be embodied in different forms without departing from the spirit and scope thereof.

What is claimed is:

1. A furnace-retort having a rotatable retort shell, mounted in respect to the masonry structure of the furnace in such a manner that heat from the furnace can be transmitted to and through the walls of the retort to the material being treated within the retort shell, the retort being gas tight, except for offtake means by which evolved vapors and gases pass from the retort, the retort being provided with means for feed.

ing coal or analogous material thereinto at one end and with means whereby the solid residues can pass from the interior of the retort at the other end, said retort also having located in said rotatable shell a bar, which is free to rise and fall as the retort rotates.

2. A furnace-retort within the retort of which coal or analogous material is subjected to a carbonizing or distilling operation by heat which is transferred by conducting from the exterior of the retort shell to the material within the retort shell and from which retort the vapors or gases are withdrawn as given off, which furnace-retort has a masonry structure providing a part of the combustion chamber of the furnace into which the shell of the retort extends, the retort shell having a longitudinally extending body member with heads secured thereto, one head at each end, each of which heads has a hollow trunnion or centrally located neck member, the shell being rotatably mounted and provided with means for rotating the same, the construction being such that the material to be treated can be fed into the retort at one end through one of the hollow trunnions or neck members, and such that the residue can pass out from the other end through the other hollow trunnion or neck member, the retort also having located therein a longitudinally extending railroad rail free to rise and fall as the shell is rotated.

3. A furnace-retort having a rotatable retort shell provided by a longitudinally extending tubular body member with two heads secured thereto, one head at each end of the body member, each head being provided with a hollow trunnion, through one of which trunnions coal is fed into one end of the retort shell, and through the other of which trunnions residue passes from the retort shell, the furnace-retort having bearing members upon which the trunnions are carried and means for rotating the retort shell, the furnace-retort also having masonry arranged to define the combustion chamber of the furnace so that the retort shell is exteriorly heated, the retort being characterized by having a longitudinally extending freely movable bar located within the body member.

4. A furnace-retort having a masonry structure providing a furnace construction within which there is located a longitudinally extending body member of the shell of the retort, the retort having at each end of the body member a head which is secured to the body member, each head having a hollow trunnion and a bearing member for the trunnion, there being means for rotating the shell, means whereby coal can be fed into the shell while the shell is being rotated, means whereby the residue can be passed

from the shell while the shell is being rotated, and means whereby evolved vapors and gases can be withdrawn while the shell is being rotated, the furnace-retort being characterized by having a freely movable bar in the form of a railroad rail located within the body member of the shell of the retort.

5. A furnace-retort having a rotatable retort shell, suitably mounted in respect to the masonry structure of the furnace, in such a manner that heat from the furnace can be transmitted through the walls of the retort to the material being treated within the retort shell, the retort being gas tight except for an offtake by means of which vapors and gases pass off from the interior of the retort, there being means for feeding coal or analogous material into one end of the retort and means whereby the solid residues are withdrawn from the other end of the retort, said furnace being characterized by having a bar located therein which is free to rise and fall as the retort rotates in order to agitate and break up material within the retort.

6. A furnace-retort within the retort of which coal or analogous material is subjected to a carbonizing or distilling operation by heat which is transferred by conducting from the exterior of the retort shell to the material within the retort shell and from which retort the vapors or gases are withdrawn as given off, which furnace-retort has a masonry structure providing a part of the combustion chamber of the furnace by which the retort shell is exteriorly heated, the retort shell having a longitudinally extending body member with heads secured thereto, one head at each end, each of which heads has a hollow trunnion or centrally located neck member, the shell being rotatably mounted and provided with means for rotating it, the construction being such that the coal can be fed in at one end through one of the hollow trunnions or neck members, and such that residue can pass out from the other end through the other hollow trunnion or neck member, the retort being characterized by having a chain extending through the opening of the trunnion or neck member at the discharge end and which chain is mounted so that it moves in engagement with the material passing through the last mentioned trunnion.

7. A furnace-retort having a masonry structure providing a furnace construction within which there is located a longitudinally extending body member of the shell of the retort, the retort having at each end of the body member a head which is secured to the body member, each head having a hollow trunnion, there being a bearing member for each trunnion means for rotating the shell and

means for feeding the coal into the shell while being rotated, the construction also being such that the solid residues can pass from the retort shell while being rotated and such that vapors and gases can be withdrawn for collection while the retort shell is being rotated, the furnace-retort being characterized by having a freely movable bar located within the body member of the shell of the retort and also by having a freely movable chain extending through the hollow trunnion at the discharge end.

8. A furnace-retort having a rotatable retort shell, mounted in respect to the masonry structure of the furnace in such a manner that heat from the furnace can be transmitted to and through the walls of the re-

tort to the material being treated within the retort shell, the retort being gas tight, except for offtake means by which evolved vapors and gases pass from the retort, the retort being provided with means for feeding coal or analogous material thereinto at one end and with means whereby the solid residues can pass from the interior of the retort at the other end, said retort having located in said rotatable shell a member which is free to rise and fall as the retort rotates.

This specification signed this eighth day ³⁰ of June A. D., 1921.

JOHN W. McLAUGHLIN.
GEORGE H. GELL.
